UNITED STATES PATENT OFFICE.

JOHN COSTELLO, OF BROOKLYN, NEW YORK.

LOOSE-LEAF BINDER.

Application filed August 8, 1922. Serial No. 580,464.

To all whom it may concern:

Be it known that I, JOHN COSTELLO, a citizen of the United States, and a resident of the city of New York, borough of Brooklyn, in the county of Kings and State of New York, have invented a new and Improved Loose-Leaf Binder, of which the following is a full, clear, and exact description.

This invention has relation to loose leaf binders and has particular reference to an improvement in that type of binders known to the trade as prong binders.

The invention contemplates a loose leaf prong binder in which the prongs are directly carried by the binder back in order when the binder is opened to permit the cover flaps to lie perfectly flat upon a supporting surface whereby prongs of a maximum length may be used.

Another feature of the invention resides in the provision of a binder of this character which includes a leaf clamping means capable of a wide opening to facilitate the insertion or removal of the leaves.

The invention further aims to provide in a loose leaf prong binder a means for retaining the prongs thereof in correlative engagement with the leaves and in which said retaining means may be readily manipulated to admit of the disengagement and relative separation of the prongs to effect the removal or application of the leaves to the binder.

As a still further object the invention aims to provide a loose leaf prong binder which is extremely simple in its construction, inexpensive to manufacture, and which is highly efficient in its purpose.

With the above recited and other objects in view, the invention resides in the novel construction set forth in the following specification, particularly pointed out in the appended claim and illustrated in the accompanying drawings, it being understood that the right is reserved to embodiments other than those actually illustrated herein to the full extent indicated by the general meaning of the terms in which the claim is expressed.

In the drawings—

Figure 1 is a perspective view of the binder with the leaf retaining means in locked condition.

Fig. 2 is a similar view with the leaf engaging means in released condition.

Fig. 3 is a detail perspective view illustrating the prong mounting.

Referring to the drawings by characters of reference, 10 designates the back member of the binding which is formed with hingedly connected opposite side portions or connecting strips 11, the free edges of which are hingedly connected to the cover flaps 12. The side portions or connecting strips 11 are provided with spaced prongs 13 projecting inwardly therefrom, which prongs are of arcuate formation to coincide with the arcuate path of movement during the swinging of the side portions or connecting strips 11 from their open to closed position. As is customary with this type of loose leaf binder, the leaves are provided with spaced apertures adjacent their inner edges conforming to the spacing of the prongs 13 whereby they may be readily associated with or removed from the binding. When opened, the side portions or connecting strips 11 are designed to lie flat and in the same plane with the back 10 whereby the prongs 13 will project vertically or at a right angle to facilitate the application and removal of the pages or leaves thereto. The means for holding the portions or connecting strips 11 at substantially a right angle to the back 10 and the prongs in correlated clamping relation to the pages comprises a coupling member 14 having hooks 15 at its opposite sides and hooks 16 engageable therewith and carried by the side portions or connecting strips 11. The coupling element is in the nature of a sliding catch mounted on a bearing plate 17 and normally forced by springs 18 in a direction to engage the hooks 15 and 16 with each other. Preferably the coupling element is slidable between the guide bars 19 and the bearing plate 17 as illustrated.

The bearing plate is provided with a base flange 20 which is secured to the back member 10 and the hooks 16 are provided with a base flange 21 which is secured to the inner face of each side portion or connecting strip 11. The coupling element is provided with a manipulating handle 22. Preferably a coupling element is provided at each of the opposite ends of the back member 10 and a hook 16 at each of the opposite ends of the side portions or coupling strips 11. The prongs 13 may be constructed in pairs from a single length of wire bent in U-form with

the eight 23 underlying a metal strip 24 embedded in the side portions 11, the legs of the U-shaped member constituting the prongs being inserted through apertures 25 in the strip 24.

In use and operation, the coupling elements 14 are normally forced under the action of the springs 18 away from the back member 10 to engage the hooks 15 with the 10 hooks 16 whereby the side portions or connecting strips 11 are disposed at a right angle to the back member 10 with the free ends of the prongs extending from each strip into close relation to the opposite strip to pre- 15clude the accidental displacement of the leaves or pages from the binding. When it is desired to remove or apply the pages, the manipulating handles 22 are depressed to disengage the hooks 15 from the hooks 16; 20 this permits of the swinging of the side portions or connecting strips outwardly and away from each other where they may lie flat and in the same plane with the back 10.

The cover flaps 12 may also be disposed 25 in the same plane with the back when the binding is open. In closing the binding, the noses of the hooks 16 will engage over the notches of the lugs 15 to depress the coupling element 14 against the action of the 30 spring without the necessity of employing

the manipulating handles 22 for this purpose.

I claim:

A loose leaf note book binder comprising a back, side strips hingedly secured to the 35 back, cover flaps secured to the side strips, substantially U-shaped prongs mounted through each side strip adapted to overlap when the book is closed, a bearing plate secured to the back by its base flange and having a vertical portion adjacent the end of the back, a spring actuated coupling member mounted for sliding movement with respect to the vertical portion of the bearing plate, means for guiding said coupling member in 40 a path of movement parallel to the vertical portion of the bearing plate, said coupling member having niches cut in its upper edge adjacent each side forming a hook at each end, and plates secured to each side strip 45 by a base flange, said plates having a vertical portion with a niche in one side forming a hook at the end of the plate adapted to enter the niches in the coupling member and the hooks of the coupling member adapted 50 to enter the niches in the plates when the side members are swung into vertical position.

JOHN COSTELLO.
